UNITED STATES PATENT OFFICE.

ROBERT W. BIRCHFIELD, OF JOLIET, ILLINOIS.

METHOD OF MAKING BOILERS.

Application filed August 4, 1923. Serial No. 655,637.

To all whom it may concern:

Be it known that I, ROBERT W. BIRCHFIELD, a citizen of the United States, and resident of Joliet, in the county of Will and 5 State of Illinois, have invented certain new and useful Improvements in Methods of Making Boilers, of which the following is a specification.

My invention relates to improvements in 10 means and methods of making parts of boilers and has special reference to improvements in the manufacture of inside wrappers or combined crown and side sheets for return tube boilers of the kind described 15 and claimed in my co-pending re-issue application Serial Number 648,347 filed June 28, 1923, and this present invention is an improvement upon the methods described and claimed in my co-pending applications, 20 Serial Number 501,068 filed September 16, 1921, and Serial Number 648,382 filed June 28, 1923.

The object of my invention is to enable the manufacture of such boilers with a minimum expenditure of time and labor and hence at a minimum cost.

Heretofore the inside wrapper sheets have required at least three operations all of which were arduous and required considerable time.

The type of boiler to which my invention relates is known as the return tube or return flue boiler and consists of a main cylindrical body, a main combustion chamber below 35 the main body portion and an auxiliary combustion chamber rising above one end of the main combustion chamber, the side walls of the combustion chamber forming the inside walls of side water legs for the boiler, 40 which depend from the main body portion.

The inside wrapper sheet, the production of which is the aim and object of my invention, consists of a single sheet formed to provide, a concave crown sheet, the inside 45 sheets or walls of the water legs, and which are the side sheets of the main combustion space of the boiler and continuations of which form the side sheets of the auxiliary combustion space.

Heretofore such inside wrappers have been formed by means of heavy rolls and breaks in several steps and as described and claimed

in my said co-pending applications, whereas by means of my present improvements I am enabled to eliminate substantially 90% of 55 the time and an equal or greater percentage of the labor.

Instead of forming the flat plate into the completed inside wrapper by the step by step forming method described and claimed 60 in my said co-pending method applications I combine all of the forming or bending operations into one so that instead of partially forming the sheet in one operation viz forming the concave crown sheet and then in a 65 second operation reversing the direction of projection of the side parts to produce the downwardly extending side sheets, I now form the concave crown sheet and the downwardly extending side sheets in one simultaneous operation.

While I preferably preliminarily cut the sheet to provide the portions which are to form the side sheets of the auxiliary combustion chamber I may and sometimes do 75 delay this step until the wrapper is formed and then I cut the sheet if it has not been cut, and straighten or flatten out these parts.

In the construction of my improved boiler as shown in my co-pending re-issue application I close the lower ends of the side water legs by portions of the side sheets bent to 80 form bottom flanges and preferably I form these on the edges of the inside wrapper sheet before the main forming operation 85 though obviously the formation of these flanges could be delayed until later or under some circumstances could be omitted altogether, as when it is best to form them on the edges of the outer wrapper.

My invention will be more readily understood by reference to the accompanying drawings in which I have illustrated a boiler of the kind to which my invention relates and also have illustrated the one main step 95 in my improved method of production together with the auxiliary steps of producing the portions which form the side sheets of the auxiliary combustion chamber.

In said drawings;

Figure 1, is a vertical, central, longitudinal, sectional view of a return tube boiler constructed in accordance with my invention;

Figures 2 and 3, are transverse, vertical, sectional views in the lines 2-2 and 3-3 respectively of Figure 1;

Figure 4, is a perspective view of an inside wrapper sheet in flat form, and showing the middle or crown portion cut at one end preparatory to forming side walls of an auxiliary combustion space and also showing bottom flanges dotted;

Figure 5, is a sectional view of the sheet in flat form shown in a press preparatory to being formed;

Figure 6, is a view similar to Figure 5 but showing the sheet as formed by the press;

Figure 7, is a perspective view of the finished inside wrapper as it leaves the press;

Figure 8, is a view similar to Figure 4, except the sheet has not been cut; and

Figure 9, is a perspective view of the sheet shown in Figure 8 as it leaves the press and showing the crown sheet cut preparatory to the last forming operation.

In said drawings 1 illustrates a boiler of the return flue type and having a substantially cylindrical main part 2 from which depend side water legs 3 and end water legs 4, and 5. The water legs enclose a combustion space beneath the main part of the boiler said combustion space comprising a main space 6 extending the length of the boiler and an auxiliary combustion space 7 rising above the rear end of the main combustion space. The gases of combustion rise from the main combustion space into the space 7 from which they flow forwardly through lower flues 8 to the forward end and return thru upper flues 9.

The shell of the boiler comprises a U-shaped outer wrapper 10, a substantially U-shaped inner wrapper 11, and suitable end sheets for closing the ends of the combustion chambers and forming the end water legs.

The inner wrapper sheet to the production of which this present invention appertains consists of a concave crown sheet portion 12 and depending substantially parallel side sheets 13 and may be provided with outwardly turned bottom flanges 14 for closing the bottoms of the side water legs of the boiler. The concave crown sheet portion 12 forms the lower part of the main cylindrical part of the boiler and is preferably curved on the same radius as the upper part 15 of the outer shell 10, as best shown in Figure 2. The main side sheet portions of the inner shell extend the length of the fire box but the crown sheet portion

12 only extends back to the forward end of the auxiliary combustion space 7. The side sheets 13 have upwardly extending parts 16 at their rear ends which extend above the crown sheet portion to form the side sheets of the auxiliary combustion chamber 7.

As the production of the bottom flanges 14 on the edges of the inner shell is optional I have shown them in dotted lines in the several figures of the drawings which illustrate my improved method.

This method consists in providing a flat sheet 17 such as illustrated in Figures 4 and 8 of suitable dimensions.

I may as a preliminary step first cut the sheet on its transverse center line as shown at 18 a distance equal to the length of the auxiliary combustion chamber and transversely at the inner end of the first cut as shown at 19. The cut 19 extends from side to side of the portion of the sheet which forms the crown sheet. Then I place the sheet in a suitable press illustrated by the upper die 20 and lower die 21 and I force the dies toward each other as shown in Figure 6 and produce in one operation the concave crown sheet 12 and depending side sheets 13. In such an operation the dies engage only the crown sheet portion the severed parts 16 being free of the press and consequently these portions are not deflected out of the planes of the side sheet portions but remain therein and extend upwardly as shown in Figure 7 when the side sheet portions are in depending position.

There is one peculiarity about the dies and that is that it is practically impossible to make the upper die to force the side sheets inwardly beyond their true positions to allow for the inherent spring of the metal and it has been found difficult to produce these inner wrappers with the side sheets parallel in this press operation. This difficulty however has been met and overcome by making the middle portions 22 and 23 of the dies curved to slightly smaller radii than is desired on the finished wrapper and also making the edge portions 24 and 25 which form the curves between the side sheets and the crown sheet likewise on slightly smaller radii that is required on the finished wrapper. These parts are made on radii sufficiently smaller than the finished product so that the inherent resilience of the plate when relieved of the pressure of the dies which tends to straighten both of these curves will be allowed for.

The straightening of the middle or crown sheet portion tends to swing the lower ends of the side sheets in too far and the straightening of the edge curves tends to swing said lower ends outwardly and the dies are proportioned to equalize these tendencies and produce the inside wrapper with parallel side sheets.

Instead of using dies short enough to bend only the main crown sheet portion it is sometimes convenient to bend the whole width of the sheet and later on straighten out the parts 16 for the side sheets of the auxiliary combustion space. When I form the inside

wrapper in this latter manner I preferably do not make the cuts 18 and 19 until after the main bending operation.

In Figure 8, I have illustrated a flat blank sheet 26 which as in the former instance may or may not have the bottom flanges 14 formed preliminarily. The sheet 26 is shown without the cuts 18 and 19. In Figure 9 I have illustrated the result of the first main bending operation except that I have illustrated the cuts 18 and 19 as having been made after the bending. Thereafter the parts 16 are straightened out and flattened and the final form of the completed inner wrapper is shown in Figure 7.

As indicated herein various changes can be made in the order of the steps of my improved method without going beyond the scope of the invention and consequently I do not limit my invention to the preferred sequence of operations.

I claim:

1. The herein described method of forming inside wrapper sheets of the kind described, which consists in providing a flat sheet of the required dimensions, subjecting the sheet to pressure and thereby distorting the sheet out of its flat condition and simultaneously forming a concave crown sheet and depending side sheets.

2. The herein described method of forming inside wrapper sheets of the kind described, which consists in providing a flat sheet of suitable dimensions, bending the sheet to form a concave crown sheet and simultaneously bending the sheet to form depending side sheets.

3. The herein described method of making the inner shell of a boiler having an auxiliary combustion space above one end of a main combustion space which consists in providing a suitable flat blank, cutting the blank inwardly from one end on its transverse center line a distance equal to the length of the auxiliary combustion space then cutting the blank transversely at the inner end of the first cut, then applying pressure to the blank and by means of the pressure applied in one bending operation bringing the transverse end portions of the blank into parallelism, the central portion into a crown sheet depending between the side portions and during which bending operation the two severed portions are separated along the cuts and are brought into parallel relation in the planes respectively of said transverse end portions to form the sides of the auxiliary combustion space.

4. The herein described steps in a method of forming an inside shell for a boiler having an auxiliary combustion space above one end of a main combustion space, the provision of a suitable flat blank of a length equal to the length of the main combustion space and a width sufficient to extend from the

lower edge of one side sheet up over and down to the lower edge of the opposite side sheet, cutting the blank inwardly from one end on its transverse center line a distance equal to the length of the auxiliary combustion space then cutting the blank transversely at the inner end of the first cut, then bending the middle portion of the sheet to form a concave crown sheet and simultaneously bending the plate at the lateral edges of the crown sheet portion to bring the transverse end portions into parallelism to form the side sheets of the shell and by which bending operation the severed portions are swung out into parallelism and into the planes of the two side sheets respectively.

5. The herein described steps in a method of forming an inside shell for a boiler having an auxiliary combustion space above one end of a main combustion space, the provision of a suitable flat blank of a length equal to the length of the main combustion space and a width sufficient to extend from the lower edge of one side sheet up and over and down to the lower edge of the opposite side sheet, cutting the blank inwardly from one end on its transverse center line a distance equal to the length of the auxiliary combustion space then cutting the blank transversely at the inner end of the first cut, then depressing the middle portion to form a concave crown sheet and simultaneously depressing the transverse end portions to bring them into parallelism to form the side sheets, and by which bending operation the severed portions are swung out into parallelism and into the planes of the two side sheets respectively.

6. The method of making an inside wrapper for a return flue boiler having an auxiliary combustion space above one end of the main combustion space which consists in providing a suitable flat sheet, bending the middle portion of the sheet to form a concave crown sheet and to simultaneously bring the edge portions of the sheet into parallelism and subsequently straightening out portions of the middle portion into the planes of the parallel portions for side sheets of the auxiliary combustion spaces.

7. The herein described method of forming an inside wrapper of the kind described which consists in providing a suitable flat sheet bending the middle portion to a curved shape, having a shorter radius than the concave crown sheet desired and simultaneously bending the sheet at the longitudinal edges of said concave portion to extend the edge portions substantially parallel to each other and extending down from the middle concave portion and said bends being on shorter radii than the finished bends desired and allowing the bends to assume their free unstrained condition whereby said end portions extend parallel to each other.

21
 8. In a pair of dies for forming a sheet into an inside wrapper of the kind described the bending portions of the dies being formed on shorter radii than the like portions of the finished wrapper whereby said portions while in the dies are over bent sufficiently to allow for the straightening of the sheet due to its resiliency when released from the dies and whereby said side sheets 10 are maintained substantially parallel.

9. The herein described method of forming an inside wrapper sheet of the kind described, which consists in providing a suitable flat sheet, and simultaneously bending 15 the middle portion and the end portions of the sheet in the same direction from the plane of the sheet to form a concave crown sheet and depending substantially parallel side sheets.

20 10. The herein described steps in forming the inner shell of a boiler, having an auxiliary combustion space above one end of a main combustion space, which method consists in providing a suitable flat sheet metal 25 blank which has certain portions to form main side sheets and other certain portions to form parts extending up from one end of the side sheets to form side sheets for the auxiliary combustion space, bending 30 the sheet to simultaneously form a concave crown sheet and depending parallel side sheets and maintaining the portions for the side sheets of the auxiliary combustion space

flat and respectively in the planes of their respective main side sheets during the simultaneous bending operation. 35

11. The herein described steps in forming the inner shell of a boiler, having an auxiliary combustion space above one end of a main combustion space, which method consists in providing a suitable flat sheet metal blank which has certain portions to form main side sheets and other certain portions to form parts extending up from one end of the side sheets to form side sheets for 40 the auxiliary combustion space, bending the sheet to simultaneously form a concave crown sheet and depending side sheets, the crown being formed on a radius shorter than the final form desired, and the free ends of the side sheets being formed in toward each other so as to incline the sheets upwardly and outwardly relatively to each other; each of the distortions being sufficient to allow 45 for the resiliency of the metal so that when the sheet is released from the bending pressure the crown will be of the desired curvature and the sides will be parallel, and preserving the auxiliary side sheet portions flat 50 and in the planes of their respective main side sheet portions during the forming operation. 55

Signed at Chicago, Illinois, this 31st day of July, 1923.

ROBERT W. BIRCHFIELD.
